UNITED STATES PATENT OFFICE.

MICHAEL EISENSCHENK, OF COLD SPRING, MINNESOTA.

PLOW-DEPRESSING MEANS.

1,171,776.

Specification of Letters Patent. Patented Feb. 15, 1916.

Application filed September 2, 1915. Serial No. 48,691.

To all whom it may concern:

Be it known that I, MICHAEL EISENSCHENK, a citizen of the United States, residing at Cold Spring, in the county of Stearns and State of Minnesota, have invented certain new and useful Improvements in Plow-Depressing Means; and I do declare the following to be a full, clear, and exact description of the invention, such as will enable others skilled in the art to which it appertains to make and use the same.

My invention relates broadly to improvements in agricultural implements, and more particularly to means for depressing the plows proper of gang plows yieldably into the earth, whereby in case said plows come in contact with rocks or other obstructions they may yield upwardly without breakage to any parts of the machine.

The object of the invention is to provide very simple and inexpensive construction for attaining the above end in a highly advantageous and efficient manner.

With this object in view, the invention resides in certain novel features of construction and in unique combinations of parts hereinafter fully described and claimed.

In describing the invention, I shall refer to the accompanying drawings wherein like reference characters designate corresponding parts through the several views and wherein:

Figure 1 is a side elevation of a gang plow equipped with plow depressing means constructed in accordance with this invention; Fig. 2 is a top plan view with parts eliminated for the sake of clearness; Fig. 3 is a perspective view of the usual plow depressing rock shaft, showing the application of an additional arm to the plow raising foot lever thereof; and Fig. 4 is a perspective view of portions of the gang plow showing the application of the improved plow depressing means thereto.

In these drawings, which constitute a part of the application, the numeral 1 indicates the portable frame of a gang plow upon which the front and rear crank shafts 2 and 3 are disposed, said shafts supporting the usual vertically movable beams 4 of the plows proper 5, these plows being raised or depressed at will by proper actuation of a horizontally disposed transversely extending rock shaft 6 having in conjunction with one of its ends, a crank arm 7 connected by

link means 8 to one of the beams 4, a plow depressing foot lever 9 likewise acting in conjunction with this end of the rock shaft whereby movement of said lever in the proper direction will depress the beams 4 simultaneously and the plows 5 carried thereby. Disposed at the opposite end of the rock shaft 6, is a rearwardly extending foot lever 10 which when depressed raises the crank arm 7 to lift the beams 4 and the plows carried thereby, while designed for the same purpose, but for actuation by hand power, is an upright lever 11.

The parts so far briefly described constitute structure which may be found on a number of well known types of gang plows, such construction having been found to be inefficient when plowing in hard ground or in earth impregnated with rocks, since sufficient pressure cannot be placed upon the foot lever 9 to retain the plows the necessary depth in the ground, while if such plows be locked in lowered position by the hand lever 11, and they come in contact with obstacles, breakage invariably takes place. Furthermore, these disadvantages are encountered when an insufficient number of draft animals is used and the driver walks by the machine rather than ride thereon. Needless to say, under such conditions, the foot lever 9 cannot be actuated, and if the hand lever 11 is locked in position to depress the plows into the earth, danger of breakage occurs. It is to overcome these most objectionable features of the present day horse-drawn gang plow, that I have primarily designed the invention. To this end, an upstanding arm 12 is rigidly secured to the foot lever 10 or directly to the shaft 6, whereby forward movement of this arm will rock said shaft in a direction to force the crank arm 7 downwardly, thus depressing the plows into the earth. For so moving the arm 12, spring means 13 is provided, such means being shown in the present application in the form of a single tensile coiled spring having its rear end connected by any preferred means to the arm 12, while its front end is so connected to the crank arm 14 of the upstanding hand lever 15, such crank arm being connected by a rock shaft or the like 16 to said lever.

The rock shaft 16 is rotatably mounted in an appropriate bearing 17 and constitutes the fulcrum of the lever, the bearing 17 being carried by an appropriate anchor mem-

ber 18 which is detachably secured to the front left hand corner of the frame 1 and which is provided immediately adjacent one end of the bearing 17 with a segmental rack 19 coacting with the locking dog 19^a of the lever 15, said lever being equipped with hand means 20 for releasing the dog and with the locking means 24 to retain the means 20 in such position as to prevent the dog 19^a from engaging the rack 19, this being essential at times for reasons to become obvious as the description proceeds.

By the use of the construction so far described, it will be evident that forward movement of the lever 15 will force the crank arm 14 forwardly thus placing the spring 13 under tension, which tension is exerted to depress the plows into the earth the necessary amount for tilling soil in which only a few stones and the like prevail, it being understood that if one or both of the plows strike obstructions, they may yield upwardly from the earth without danger of breakage to any parts of the machine, this being due to the tensibility of the spring 13. When, however, it is necessary to plow earth in which the plows must yield upwardly a great number of times, and often very forcibly, it becomes expedient to provide yielding tensioning means for normally retaining the spring 13 under the proper tension yet which will itself yield when such spring has expanded to its utmost, thus preventing breakage thereof. For this purpose, a torsional tension spring 22 is carried by the anchor member 18, such spring being provided at one end with a laterally extending arm 23 which has connection with the lever 15 through the instrumentality of the link 24, the torsional tension of the spring 22 being normally exerted to force the arm 23 forwardly, thereby retaining the lever 15 in substantially upright position if the dog 19^a be retracted, and thereby placing the spring 13 under the proper tension. When now this spring 13 must yield small amounts for allowing the plows to move upwardly to slight extents only, the spring 22 will merely retain the lever 15 in proper upright position, but if strain so great as to have a tendency to snap the spring 13 be placed thereon, the crank arm 14 will be shifted rearwardly, thus so shifting the lever 15 against the tension of said spring 22, the latter being now placed under more forcible tension than previously and serving to again return the parts to their normal positions after the plows have passed the obstruction.

The anchor member 18 may be of practically any preferred formation, but as shown in the drawings it comprises two end plates or sections 18^a and 18^b respectively, bolted or otherwise secured at their lower ends to the frame 1, the spring 22 being interposed between the two plates and having

its end remote from the arm 23, anchored in any preferred manner. This construction is preferable on account of its extreme simplicity, durability, and efficiency, but it need not be followed too closely, since practically any preferred means at this point would accomplish the desired results.

From the foregoing description, taken in connection with the accompanying drawings, it will be evident that although very simple construction has been provided for carrying out the object of the invention, the improved parts will be highly efficient in operation and will possess a number of advantageous features. Furthermore, such parts may be easily secured to most types of horse-drawn gang plows now on the market.

In the drawings, certain specific details of construction have been shown for accomplishing probably the best results, and in the foregoing such details have been described, but it will be evident that I need not be limited thereto otherwise than to the extent to which the appended claims restrict me.

I claim:

1. A plow depressing attachment for gang plows including an anchor member to be attached to the plow frame, a coiled torsional spring anchored to said member, an arm projecting laterally from said spring, and a lever fulcrumed to said member and having connection with said arm, the lever being adapted for connection with the plow depressing means of the plow.

2. A plow depressing attachment for gang plows comprising an anchor member for attachment to the frame of the plow, a segmental rack carried by said member, a plow depressing lever fulcrumed on said member and having a dog coacting with said rack, and a coiled spring carried by the member and having connection with said lever.

3. A plow depressing attachment for gang plows comprising an anchor member for attachment to the frame of the plow, a segmental rack carried by said member, a plow depressing lever fulcrumed on said member and having a dog coacting with said rack, a coiled torsional spring carried by said member, and an arm projecting laterally from said spring and having connection with the lever.

4. Plow depressing means comprising a shaft to be rocked forwardly to move the plows downwardly, an arm having connection with said shaft and rising therefrom, an additional upright arm in advance of the other arm, spring means for yieldably retaining the second arm in upright position, and a connection between the two arms.

5. Plow depressing means comprising a shaft to be rocked forwardly to move the plows downwardly, an arm having connection with said shaft and rising therefrom,

an additional upright arm in advance of the other arm, spring means for yieldably retaining the second arm in upright position, and a coiled spring connecting the two arms.

- 5 6. Plow depressing means comprising a shaft to be rocked forwardly to depress the plows, an arm having connection with said shaft and rising therefrom, a second arm mounted in advance of the shaft for oscillation longitudinally of the plow, a connection between the two arms, a hand lever for operating the second arm at will, means for locking said lever against movement or for allowing it to swing freely, and a spring 10 for yieldably holding the lever against movement when the locking means thereof is released.

15 7. Plow depressing means comprising a shaft to be rocked forwardly to depress the plows, an arm having connection with said

shaft and rising therefrom, a second arm mounted in advance of the shaft for oscillation longitudinally of the plow, a connection between the two arms, a hand lever for operating the second arm at will, means for locking said lever against movement or for allowing it to swing freely, a coiled torsional spring having one end anchored, and an arm rising from the other end of said spring and having connection with the lever, whereby to hold the latter yieldably against movement when its locking means is released. 25 30

In testimony whereof I have hereunto set my hand in presence of two subscribing witnesses.

MICHAEL EISENSCHENK.
